CLAIM

The ornamental design for a fluid administration syringe, as shown and described.

DESCRIPTION

FIG. 1 is a perspective view of a fluid administration syringe with the plunger fully inserted in the barrel showing our new design;

FIG. 2 is a perspective view of a fluid administration syringe with the plunger fully removed from the barrel;

FIG. 3 is a front elevation view thereof;

FIG. 4 is a back elevation view thereof;

FIG. 5 is a left-hand side elevation view thereof;

FIG. 6 is a right-hand side elevation view thereof;

FIG. 7 is a top plan view thereof; and,

FIG. 8 is a bottom plan view thereof.
